WRITING INSTRUMENT FILLING DEVICE

Nathan Zepelovitch, New York, N. Y., assignor, by mesne assignments, to Nahum A. Bernstein, New York, N. Y.

Application October 10, 1956, Serial No. 615,047

15 Claims. (Cl. 141—30)

This invention relates to filling devices for writing instruments and particularly to an automatic filling device for fountain pens. This application is a continuation-in-part of my application Serial No. 502,884, filed April 21, 1955 now abandoned for Writing Instrument Filling Device.

Conventional fluid ink fountain pens are usually filled by the pumping action of an internally disposed filling mechanism which creates successive pressure variations within the ink reservoir of the pen in response to manual actuation of a plunger or a lever. The conventional filling mechanisms utilizing either a plunger or a lever, in addition to necessarily limiting the space available for an ink reservoir within the barrel of the writing instrument are, due to lack of space, usually relatively delicately constructed. This construction usually results in increase in both the production and ultimate cost of the unit and also oftentimes results in a shortened useful life of the unit due to breakage or other defect of the filling mechanism.

Apart from the above, filling of the conventional type fountain pen is usually a rather inconvenient and relatively sloppy procedure requiring a careful insertion, depthwise, of the writing instrument into the ink supply and the maintenance of that position during the filling operation. Certain common expedients, such as tiltable bottles or bottles having an auxiliary internal well disposed adjacent the neck thereof, are conventionally utilized to ameliorate this defect and to maintain a predetermined required ink level for filling purposes. In any event, filling of the conventional type writing instrument is usually accompanied by a required cleansing of the portion of the pen barrel adjacent the writing tip. An attempt to obviate this objectional feature has been revealed by recent developments in the field wherein a retractable tube is utilized for filling purposes. However, use of such an expedient necessarily adds to the manufacturing difficulties and ultimate cost of the finished product.

This invention may be briefly described as a fluid ink writing instrument filling device for automatically effecting a simple, rapid, clean and efficient filling of fluid ink writing instruments. The invention includes a manually deformable member in association with an automatically operable valve member for effecting, in timed relation, the necessary sequential pressure variations for automatic evacuation and filling of the ink reservoir of a writing instrument insertable in operating relationship therein with writing fluid.

Among the advantages attendant the present invention are the provisions of a self-contained leak-proof fluid ink supply having the filling device permanently secured thereto in hermetic relation, the elimination of the soilage hazards conventionally attendant the filling of fluid ink writing instruments, a permitted more efficient utilization of the reservoir capacities of present day fountain pens and the permitted simplification of fountain pen-type writing instruments through the dispensing of any neces-

sity for inclusion of self-contained filling mechanisms therein with its attendant cost savings to the general public.

The primary object of this invention is to provide a simple and automatic filling device for fluid-type writing instruments.

Another object of this invention is to provide a fluid-type writing instrument filling device disposed externally of and separate from the writing instrument thereby permitting utilization of an ink reservoir in fountain pens of greater capacity than heretofore possible through the permitted dispensing of an integral filling mechanism.

A further object of the invention is to provide an automatic filling device for fountain pens that is simple and inexpensive in construction and which permits a fountain pen to be filled with writing fluid in a rapid, clean and simple manner.

Still another object of this invention is the provision of a leak-proof fluid ink container that permits automatic filling of fluid ink writing instruments and is of a character that is simply and inexpensively constructed.

Other objects and advantages of the invention will be pointed out in the following disclosure and claims and illustrated in the accompanying drawings which describe by way of example the principle of the invention and the presently preferred embodiments of the filling device applying this principle.

Fig. 24 is a sectional view of still another modified construction of an automatic writing instrument filling device incorporating the principles of this invention.

Referring to Figs. 1-3, one embodiment of an automatic writing instrument filling device incorporating the principles of this invention is there illustrated in static operative relationship with a fluid ink container. As there illustrated the filling device is permanently mounted in hermetic relation on a suitable receiving flange 10 formed above the threaded neck portion 12 of an ink container 14. A suitable closure cap, as illustrated by the dotted lines 16, adapted to engage the threaded neck portion 12, may be provided to cover the complete unit when not in use. In this embodiment there is included a horizontally disposed deformable diaphragm member 18 suitably formed or molded from rubber or other suitable deformable and resilient material and premounted in hermetic relation with the container 14. Integral with the diaphragm 18 and preferably centrally disposed with respect to the neck 12 of the container 14 is an upwardly extending writing instrument-receiving member 20 having a readily deformable bore 22 contoured to receive and engage the varying size nib portions of various types and sizes of fountain pens in air and liquid-tight engagement. Dependent from and integral with the lower end of the writing instrument receiving member 20 and in air and fluid communication with the interior bore thereof is an elongated tube 24 preferably shaped as illustrated in Fig. 3, and made of the same rubber or other deformable material as is the remainder of the unit. The tube 24 should be of a length sufficient to extend well into the fluid ink disposed within the ink container 14. The shape of the writing instrument-receiving bore 22 and the tube 24, together with their deformability, permits utilization of the unit with fountain pens of almost every nib configuration including those of the so-called shrouded nib construction. As illustrated in Fig. 2, in the illustrated unitary construction, it is also preferable to include a ring 26 of metal immediately adjacent the junction of the writing instrument-receiving unit 20 and the surface of the diaphragm 18 to aid in uniform deformation in operation and to add to the mechanical strength of the unit. The diaphragm member 18 is provided with a small pressure relief passage 28 which is adapted to be closed by a valve member generally designated 30. The valve member 30, as illustrated in Figs. 1 and 2, may comprise a flap of deformable material such as rubber, secured as at 32 adjacent to the passage 28 and of sufficient extent to overlie the passage 28 as at 34.

In operation of the illustrated unit, the closure cap 16 is removed from the ink container 14 and the nib portion of a writing instrument such as a fountain pen is inserted into the bore 22 of the writing instrument-receiving member 20 so that the inserted unit is hermetically engaged thereby and the writing point thereof is in direct communication with the dependent tube 24. Manual downward depression of the fountain pen results in a deformation of the diaphragm member 18 into the container 14 and in an accompanying initial pressure increase therewith due to the decrease in volume thereof. The initial pressure increase within the ink container 14 is automatically relieved by the upward displacement

of the valve member 30 in response thereto. The automatic actuation of the valve member 30 permits an outward displacement of air from within the ink container to the atmosphere through the passage 28 and thereby permits a continual equalization of the pressure within and without the ink container 14 and within the ink reservoir of the pen being filled. When the manual downward displacement of the fountain pen is halted and an upward displacement thereof is then permitted by the reformation of the deformable diaphragm 18, the pressure within the ink container 14 is initially decreased due to the increase in volume within the container. The decrease in pressure within the ink container results in immediate closure of the pressure relief passage 28 by the valve member 30 under the influence of external atmospheric pressure. Further upward displacement of the fountain pen and diaphragm 18 results in a further pressure decrease within the container. This pressure decrease within the container in combination with the atmospheric pressure extant within the ink reservoir of the pen being filled effects a pressure unbalance which results in an automatic evacuation of the contents of the reservoir of the pen via the writing instrument-receiving unit 20 and tube 24 and in a lowering of the pressure within the pen's ink reservoir.

When the diaphragm 18 assumes its undeformed position, sufficient air will leak in around the flap-type valve 30 to permit an air flow into the container 14 and an equalization of atmospheric pressure both within and without the container. This increase to atmospheric pressure within the container in combination with the now reduced pressure within the ink reservoir of the pen results in a forcing of fluid ink into said ink reservoir through the tube 24 and the writing instrument-receiving unit 20.

Figs. 4 and 5 illustrate an alternative type of valve construction for use with the previously described embodiments of the invention. As shown in Figs. 4 and 5 the deformable diaphragm 18 is provided with a pressure relief passage 28 as previously described. The illustrated valve member, generally designated 36, includes a strip of deformable material 38 such as rubber secured at either end, as at 40, and biased so that when the diaphragm member 18 is in undeformed condition the center portion 42 thereof is disposed slightly above the surface of the diaphragm and out of engagement with the pressure relief aperture 28 therein. In operation of this type of valve member, deformation of the diaphragm 18 in response to manual depression of a fountain pen will result in a stretching of diaphragm 18 and the strip 38, and in a closure of the aperture 28 by the central portion 42 thereof during the reformation of the diaphragm until the diaphragm returns to its undeformed condition at which time the valve will automatically open.

Figs. 6 and 7 illustrate still another alternative type of valve construction for use with the previously described embodiments of the invention. In this embodiment the pressure relief passage is formed of a radially disposed narrow slit 44 in the surface of the deformable diaphragm member 18. The radially disposed slit 44 is preformed so that the defining edges thereof are upwardly disposed and thereby serve the dual function of defining a readily closable pressure relief passage as well as to provide adjacent properly disposed surfaces against which atmospheric pressure may operate to close the defined slit 44. In operation of a unit equipped with this type of valve construction, downward depression of the center of the diaphragm results in an elongation of the radially disposed pressure relief passage and in a narrowing of the width of the slit, with absolute closure thereof being prevented by the increase in pressure within the container. Reformation of the diaphragm in response to release of the manual downward deforming pressure results, as explained in detail earlier in this specification, in a momentary decrease of the pressure within the container below that of atmospheric pressure. This pressure unbalance

will result in a closure of the slit 44 by the external atmospheric pressure and in a maintenance of said closure until the diaphragm returns to or closely approaches its undeformed configuration at which time the slit 44 will automatically reopen and subject the interior of the container to atmospheric pressure.

Turning now to Figs. 8-16, which illustrate the presently preferred embodiment of the invention, there is provided a generally cylindrical ink container 50 of glass or clear plastic having a well 52 centrally disposed in the preferably downwardly sloping base portion thereof to permit maximum utilization of a fluid ink supply 54 contained therein. The upper portion of the illustrated container 50 is provided with a pair of internally directed shoulders 56, 58 in staggered relationship with the shoulder 58 being disposed inwardly from and somewhat above the shoulder 56. The lower shoulder 56 is of sufficient depth to accommodate the dependent peripheral edge portion 60 of an annular apertured closure cap 62 and to provide an outer surface of smooth and uniform external diameter and of pleasing appearance. The closure cap 62 may be conveniently molded of suitable plastic and the horizontally disposed upper surface 64 thereof is provided with a pair of relatively small circular apertures 66 and 68 and a preferably centrally disposed relatively large aperture 70. As illustrated in the drawings the relatively small apertures 66 and 68 are disposed on either side of the centrally disposed relatively large aperture 70 and are positioned so that the centers of all the apertures are disposed on a diameter of the cap 62.

The upper shoulder 58 of the container 50 is of sufficient depth to accommodate the dependent peripheral edge portion 72 of a resilient deformable member, generally designated 74, and to provide for a permanent hermetic engagement thereof intermediate the adjacent sidewall 76 of the container 50 and the adjacent inner surface of the independent edge portion 60 of the closure cap 62. If desired, suitable adhesives may be used during assembly to permanently secure the closure cap 62 to the container 50 and the dependent edge 72 of the deformable member 74 to the container 50 and the dependent edge 60 of the closure member 62 although careful proportioning of the dimensions of the various members will permit the attaining of the desired permanent hermetic sealing relationship by a press fit.

The deformable member 74, which may be molded of rubber or other suitable resilient deformable material or may be formed by a latex-dipping operation, is shaped to provide a dependent peripheral edge portion 72 as above mentioned and a relatively thin circular body portion 78 having a relatively small centrally disposed writing instrument-receiving aperture 80 disposed in axial relationship with the aperture 70 in the closure cap 62. In addition thereto, the body portion 78 is provided with a small venting aperture 82 spaced a predetermined distance from said writing instrument-receiving aperture so as to be disposed beneath the portion of the cover member positioned intermediate one of the relatively small apertures 66 or 68 and the centrally disposed relatively large aperture 70 therein. The writing instrument-receiving aperture 80 is sized to engage the nib portion of a writing instrument inserted therein and to be deformed thereby so as to surround, in substantially hermetic engagement, the barrel or other portion of the writing instrument disposed above the nib thereof.

Dependent from the underside of the deformable member 74 and formed integral therewith is a dependent conduit member 84. As best shown in Figs. 10, 12 and 13, the conduit member 84 is provided with a circular upper portion 86 at the point of juncture with the underside of the body portion 78 of the deformable member 74 and is concentrically disposed around the writing instrument-receiving aperture therein. The circular upper portion 86 merges into a flattened section 88 of generally rectangular cross-section disposed closely adjacent

the underside of the body portion 78 of the deformable member 74. Said flattened section 88 is formed so that the inner surfaces thereof are normally disposed in substantially liquid-tight contact as at 90. This configuration may be suitably formed during or after the molding or dipping operation and if desired an increased wall thickness may be provided at this location to aid in the obtaining and maintaining of a substantially liquid-tight seal therat.

As best shown in Fig. 12 the dependent portion 92 of the conduit member 84 is of sufficient length to extend closely adjacent the bottom of the well 52 when the illustrated component elements are disposed in their static position as illustrated in Fig. 10. The dependent portion 92 of the conduit member 84 is of substantially rectangular cross-section and of gradually decreasing transverse dimension. The dependent end 94 thereof is of relatively small dimension and is preferably formed with an increased wall thickness so as to assure maintenance of the opening 96 therein under all conditions of operation.

Disposed intermediate the upper surface of the deformable member 74 and the underside of the closure cap 62 is a displaceable pressure plate generally designated 100. The pressure plate 100 includes a pair of upwardly directed button members 102 and 104 positioned within, and sized to be displaceable through, the relatively small apertures 66 and 68 of the cover plate 62 and an upwardly directed writing instrument-receiving member 106 sized to be displaceably contained within the relatively large aperture 70 in said closure cap. The writing instrument-receiving member 106 is provided with an enlarged bore 108 on the upper surface thereof in axial relationship with the aperture 80 in the deformable member 74 and is sized to receive and position the barrel portion of a writing instrument insertable therein. Intermediate the button member 102 and the writing instrument-receiving member 106 is a circular venting aperture 110 formed by the downwardly directed annular flange 112. The annular flange 112 is positioned and sized to be disposed within the venting aperture 82 in the deformable member 74 as best illustrated in Fig. 10 and to thereby define the size of the venting aperture 110 in the assembled unit.

The circular aperture 110 is covered by a pressure displaceable valve member generally designated 114. As best shown in Figs. 10, 11 and 14-16, the valve member 114 may comprise a flap 116 of deformable material such as rubber or plastic, secured as at 118 adjacent to the aperture 110 and of sufficient length to overlie said aperture as at 120. Cooperating with the valve member 114 is a venting channel 122 on the upper surface of the pressure plate 100. The venting channel 122 is of a length to extend slightly beyond the edge portion of the flap 116 and terminates within the aperture 110. As best shown in Figs. 14 and 15, the venting channel 122 is of gradually increasing depth, with the point of greatest depth coming at the intersection thereof with dependent annular flange 112 defining the aperture 110.

In an assembled unit the static positioning of the component parts is as shown in Fig. 10. As illustrated the deformable member 74 maintains the pressure plate 100 biased against the underside of the closure cap 62, thereby maintaining the valve member 114 over the venting aperture 110 and biased thereagainst. The flattened section 88 of conduit member 84 has, as described earlier, its inner surfaces disposed in liquid-tight relationship. The only opening into the interior of the container with the parts so positioned is at the juncture of the venting channel 122 and the edge of the valve flap 116. This opening is of such diminutive size, however, that absent a pressure differential, the surface tension of the fluid ink prevents passage therethrough even when the container 50 is inverted or shaken. By the above construc-

7
tion, there is provided, in the practical sense, a leak-proof unit.

In operation of the above described unit, the nib portion of a writing instrument such as a fountain pen is then manually inserted into the bore 108 of the writing instrument-receiving member 106 and the nib portion thereof is guided thereby and introduced into the receiving aperture 80 in said deformable member 74. A slight downward pressure on the inserted writing instrument results in insertion of the nib portion thereof into the normally sealed portion 90 of the flattened section 88 of the conduit member 84 and in hermetic engagement of the barrel or other portion of the writing instrument disposed immediately above the nib portion thereof by the now deformed aperture 80. With the writing instrument so positioned the inserted nib portion will be closely surrounded by the previously flattened portion 90 of the conduit member 84. When properly inserted as set forth above, the barrel or other portion of the writing instrument will be hermetically engaged by the now deformed aperture 80 in the deformable member 74 and the ink reservoir of the writing instrument will be in direct communication with the interior of the container 50 through the dependent conduit member 84. With the pen so positioned, a manual downward depression of the button members 102 and 104 relative to the closure cap 62 results in a downward displacement of the pressure plate 100. The downward displacement of the pressure plate 100 effects a concomitant downward displacement of the deformable member 74 and deformation of the same. The downward displacement of the deformable member 74 results in a volume decrease within the container 50. The pressure increase within the container 50 accompanying the volume decrease therewithin is automatically relieved through the venting aperture 110 by the upward displacement of the portion of valve member 114 lying thereover in response to the difference between the atmospheric pressure and that extant within the container. The venting aperture 110 is sized so as to permit an unimpeded outflow of air at a sufficient rate during the downward displacement of the deformable member 74 to prevent any substantial pressure buildup within the container 50 at that time. As such, during the downward displacement of the deformable member 74 sufficient air will escape from the interior of the container 50 through the venting aperture 110 so as to maintain the pressure within the container substantially equivalent to that of the atmosphere externally of the container. Since the pressure extant within the ink reservoir of the writing instrument is also equal to that of the atmosphere no fluid or air flow will take place into or therefrom through the conduit 84.

When the manual downward displacement of the pressure plate 100 is halted, a release of the button members 102 and 104 results in an immediate and rapid upward displacement of the pressure plate 100 in response to reformation of the deformable member 74 to its undeformed condition. The rapid initial upward displacement of the deformable member 74 results in rapid volume increase within the container 50 and attendant pressure decrease therewithin. This rapid decrease in pressure within the container 50 in conjunction with the atmospheric pressure acting on the upper surface of the flap 116 results in an immediate closure of the venting aperture 110. As the deformable member 74 continues its upward displacement during its reformation the pressure within the container 50 continually decreases. This pressure decrease, in conjunction with the atmospheric pressure theretofore extant both within and without the ink reservoir of the pen being filled effects a rapid pressure unbalance which results in an automatic evacuation of the contents of the ink reservoir through the conduit member 84. The evacuation of the pen reservoir as described above will continue until the pressure

8
extant within the ink reservoir closely approximates that extant in the container 50.

The reformation of the deformable member 74 in its return to its static position as illustrated in Fig. 10 is relatively rapid. During the initial stages of said reformation the overlying peripheral portions of the flap 116 will effectively, if not completely, fill the shallow end of the venting channel 122. If any air does pass therethrough the amount is so small and the reformation time is so short that it has no noticeable effect on the rapidly increasing pressure unbalance.

As the deformable member 74 approaches its undeformed condition the ink reservoir will be evacuated as described above. Thereafter the pressure decrease within the container 50 reaches a maximum and the action of the atmospheric pressure upon the upper surface of the flap 116 will tend to force the flap into the venting aperture 110 and assume the configuration schematically shown in Fig. 16. Such deformation of the flap 116, however, only serves to open the venting channel 122 and to permit a rapid inflow of air into the interior of the container 50 with a consequent pressure increase therein. As the pressure within the container gradually approaches that of the atmosphere due to the admission of air therein through the venting channel 122 a pressure unbalance is created with respect to the evacuated ink reservoir of the writing instrument. The pressure increase within the container in combination with the previously reduced pressure within the ink reservoir of the writing instrument results in the forcing of the fluid ink 54 into said ink reservoir through the conduit 84 and in a complete filling thereof.

The maintenance of substantial pressure equalization during the downward displacement of the deformable member 74 is essential for efficient operation of the above described unit during filling operations and also to prevent actuation of the unit by depression of the button members 102 and 104 without a writing instrument mounted thereon in filling relationship. If a pressure buildup is effected within the container 50 during depression of the pressure plate 100, fluid ink may be forced through the flattened sealing area 90 of the conduit member 84 and geyser out of the aperture 80 if the same is open or break the seal at the aperture 80 if a writing instrument is positioned therein, with the obvious soilage hazards attendant thereto. In order to minimize this possibility it is desirable to make the flattened section 88 of the conduit member 84 of increased wall thickness so as to render the seal 90 therein of such character as to assure that a lesser amount of pressure within the container 50 will be required to actuate the valve 114 than will be required to open the seal 90.

Figs. 17 and 18 illustrate an alternative type of valve construction which may be employed in lieu of the valve construction described in the immediately preceding embodiment of the invention. The venting aperture and valve assembly are integral portions of the deformable member 74. More specifically, the deformable member 74 is provided with a radially disposed slit 128 having the defining side walls 130 thereof upwardly disposed relative to the upper surface of the deformable member 74 and of sufficient size to permit collapse thereof by action of atmospheric pressure whenever the pressure within the container is reduced. As shown in the drawings, the radially disposed slit is preformed so that it is normally biased in closed position absent any pressure differential between that of the atmosphere and that extant within the container 50. Although the slit 128 is normally closed, one of the upwardly directed defining side walls thereof is provided with a recessed venting channel 132, which functions in a similar manner to that of the venting channel 122 heretofore described.

If this particular embodiment of valve structure is employed, the heretofore described annular flange 112 may

be omitted and the pressure plate 100 is formed to provide a radially disposed narrow slit therein to accommodate the upwardly directed slit defining side wall members 130.

In operation of a unit equipped with this type of valve construction any pressure increase within the container resulting from downward displacement of the pressure plate 100 causes the slit 128 to open and permit air to readily escape therethrough. Upon release of the pressure plate 100, reformation of the deformable member 74 results, as explained in detail earlier in the specification, in an initial and rapid pressure decrease within the container 50 below that of atmospheric pressure. The pressure decrease within the container 50 in conjunction with the action of atmospheric pressure externally on the upwardly directed side walls 130 of the valve will result in automatic closure of the venting aperture or slit 128 and the operational cycle will continue as heretofore described in detail for the previously discussed embodiment. During and after reformation of the deformable member 74 air will leak in through the venting channel 132 to permit the desired pressure buildup within the container 50 and force fluid ink into the ink reservoir of the writing instrument being filled.

As discussed earlier in this specification, the unit illustrated in Figs. 8-16 is, for all practical purposes, leak-proof. A small amount of fluid ink, however, may be removed from the unit by turning the unit upside down and then manually actuating the pressure plate 100. In order to reduce the possibility of inadvertent actuation of the pressure plate 100 when the unit is inverted, as might possibly occur for example if the unit were dropped, the closure cap 62 may be formed as illustrated in Fig. 19. As there shown, the closure cap 62 is of increased depth and is provided with a pair of hemispherically-shaped recesses 140 surrounding the button members 102 and 104. Such construction places the upper surface of the closure cap 62 at a height equal to or slightly above the upper surface of the button members 102 and 104.

Fig. 20 illustrates a modified construction of an automatic writing instrument filling device incorporating the principles of this invention. In this embodiment the deformable member 144 is in the form of an annular ring having a dependent peripheral edge portion 146 adapted to be hermetically secured to the container 143 and provided with a relatively large centrally disposed circular aperture 150. Secured in hermetic relation to the upper surface of the deformable member 144 and covering the aperture 150 therein is a pressure plate generally designated 152. The pressure plate 152 is provided with a pair of upwardly directed button members 154 and 156 disposed on either side of an upwardly directed centrally disposed annular flange or collar portion 158. The collar portion 158 is provided with an axially disposed bore 160 having a conduit member 162 secured thereto. The conduit member 162 is preferably of the same configuration as that of the previously described conduit member 84 and is preferably formed of plastic or other suitable material. The outer surface of the collar portion 158 is provided with an annular recess 166 adapted to receive and position in hermetic relationship the beaded periphery of a resilient deformable writing instrument-receiving member 168 mounted thereon. The writing instrument-receiving member 168 (see Figs. 21 and 22) is provided with a centrally disposed aperture 170 on the upper surface thereof overlying the bore 160 which is sized to deformably receive the nib portion of a writing instrument and to provide a hermetic engagement of the barrel or other portion of the writing instrument disposed above the nib thereof upon insertion of the writing instrument therein as described in detail earlier in this specification. Formed integral with the writing instrument-receiving member 168 is a valve flap member 172 positioned to overlie a venting aperture 174 disposed in the surface of the pressure plate 152. A closure cap 176 apertured as at 178 and 180 to displace-

5 ably receive the button members 154, 156 and provided with a raised central section 182 having a centrally disposed aperture 184 therein disposed in axial alignment with the aperture 170 in the writing instrument-receiving

10 member 168 is provided to cover the above described elements and to provide a finished unit of attractive appearance.

15 As was the case in the previously described embodiment the upper surface of the pressure plate 152 is provided with a venting channel 186 similar to that illustrated in Figs. 14-16 and terminating at the venting aperture 174.

15 The operation of the above-described unit is essentially similar to that described earlier in this specification for the embodiment illustrated in Figs. 8-16.

20 Fig. 23 illustrates another modified construction of an automatic writing instrument-filling device incorporating the principles of this invention. In this embodiment the ink container itself is made of deformable material and the necessary pressure variations are effected by deformation of the container. As there illustrated, there is provided a generally cylindrical ink container 183 having a downwardly sloping base portion 185 to permit maximum utilization of a fluid ink supply 187 contained therein. The container 183 is provided with an annularly-shaped and inwardly directed wall portion 189 of reduced thickness and a horizontally disposed pressure plate 188. The pressure plate 188 is formed so as to provide a pair of upwardly extending button members 190, 192, a venting aperture 194 and a centrally disposed upright collar or flange portion 196. Integral with or secured to the flange portion 196 is a dependent conduit member 198 of the same general shape as heretofore described. In this embodiment the container 183, the wall section 189 thereof, the horizontally disposed plate member 188, and the conduit member 198 all constitute a single unit which may be molded of suitable plastic materials, such as that conventionally employed in the so-called "squeeze" bottles for the dispensing of liquids.

25 30 35 40 45 50 Hermetically mounted around the upright collar or flange portion 196 is a resilient deformable writing instrument-receiving member 200 of the type illustrated in Figs. 21, 22, formed of rubber or suitable material. The writing instrument-receiving member 200 is provided with a centrally disposed writing instrument-receiving aperture 202 and integral flap valve 204 mounted on one side thereof and positioned to overlie the venting aperture 194 in the horizontally disposed pressure plate 188. As was the case with the earlier described embodiments, a venting channel is provided in the upper surface of the pressure plate 188 intersecting the venting aperture 194 therein.

55 60 65 In the illustrated embodiment, there is also provided a closure member 206 having the dependent edge portions thereof secured to the container 183 and shaped to provide a pair of hemispherically-shaped recesses 208 and 210 on the upper surface thereof surrounding the actuating buttons 190 and 192 as illustrated in Fig. 19 and described earlier in this specification. In this embodiment there is additionally provided a protective collar member 212 surrounding the writing instrument-receiving member 200 and having an aperture 214 therein disposed in axial alignment with the writing instrument-receiving aperture 202.

70 75 The operation of this unit is essentially similar to that described in detail for the other embodiments earlier in this specification except that herein a downward depression of the button members 190 and 192 results in a downward displacement of the pressure plate 188 and in an inward deformation of the side wall portions 189 and consequent volume decrease within the container.

Fig. 24 illustrates still another modified construction of an automatic writing instrument-filling device incorporating the principles of this invention. In this embodiment, the container 220 is generally parabolic in shape and is formed of suitable plastic material, such as that

conventionally employed in the so-called "squeeze" bottles for the dispensing of liquids. Dependent from the apex of the generally parabolic-shaped container 220 is a downwardly directed integral dependent sleeve member 222 having the dependent end thereof turned upwardly as at 224 to provide an annularly-shaped writing instrument-receiving member 226 recessed. Integral with or hermetically secured to the edge of the upwardly turned portion 224 is a dependent conduit member 228 of the same general configuration as heretofore described earlier in this specification. Disposed within the receiving recesses 226 is the dependent edge portion 230 of an annularly-shaped writing instrument-receiving member 232. The writing instrument-receiving member 232 is provided with a writing instrument-receiving aperture 234 on the horizontally disposed upper surface thereof and an integral flat valve 236 sized and positioned to overlay a venting aperture 238 in the side wall of the dependent sleeve member 222.

The upper portion of the sleeve member 222 is provided with a relatively rigid writing instrument-positioning washer 240 which serves to position the barrel portion of a writing instrument inserted therein and as a sealing seat for a removable closure plug 242 sized to provide a closure for said dependent sleeve 222 when the unit is in use and to cover the valve member therein.

The operation of this unit is essentially similar to that described in detail at an earlier point in the specification in conjunction with the other embodiments of the invention except that herein the reduction in volume within the container 220 is effected by deformation of the container itself as by direct manual application of pressure to the wall portion thereof as at 244.

In accordance with the provisions of the patent statutes, I have herein described the principles of this invention, together with the elements which I now consider to constitute a workable embodiment thereof, but I desire to have it understood that the structure disclosed is only illustrative and the invention can be carried out by other means. Also, while it is designed to use the various features and elements in the combinations and relations described, some of these may be altered and modified without interfering with the more general result outlined.

It is claimed:

1. A device for automatically filling writing instruments of the type having an ink reservoir and a writing tip in fluid communication therewith comprising an ink supply container, a writing instrument-receiving unit shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, means associated with said container for effecting a volume reduction therewithin, said last mentioned means having a pressure relief passage therein connecting the interior of said container with the atmosphere externally of said container sized to permit substantial maintenance of atmospheric pressure within said container during volume reduction thereof, valve means responsive to the difference in pressure between that of the atmosphere external of said container and that within said container for selectively closing said pressure relief passage during a volume increase therewithin and for permitting the pressure within said container to return to that of the external atmosphere after the volume of said container is returned to its original volume.

2. A device for automatically filling writing instruments of the type having an ink reservoir and a writing tip in fluid communication therewith comprising an ink supply container, deformable means for effecting a volume decrease therewithin, a writing instrument-receiving unit shaped to engage the writing tip of a writing instrument inserted therein in substantially hermetic relationship, a

conduit member dependent from said writing instrument-receiving unit for connecting the ink reservoir of a writing instrument inserted in said receiving unit in fluid communication with the interior of said container, said deformable means having a pressure relief passage therein connecting the interior of said container with the atmosphere externally of said container sized to permit substantial maintenance of atmospheric pressure within said container during deformation of said deformable means effecting a volume reduction therewithin, valve means responsive to the reformation of said deformable means and to the difference in pressure between that of the atmosphere external of said container and that within said container for selectively closing said pressure relief aperture during reformation of said deformable means and means associated with said valve means and pressure relief passage for permitting the pressure within said container to return to that of the external atmosphere subsequent to reformation of said deformable means.

3. A device for filling writing instruments of the type having an ink reservoir and a writing tip in fluid communication therewith comprising an open-ended ink supply container, deformable means hermetically secured to the open end of said ink supply container and displaceable thereinto for effecting a volume decrease therein, a writing instrument-receiving unit mounted on said deformable means shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, said deformable means having a pressure relief passage therein connecting the interior of said container with the atmosphere externally of said container sized to permit substantial maintenance of atmospheric pressure within said container during deformation of said deformable means inwardly of said container, valve means associated with said pressure relief passage responsive to the difference in pressure between that of the atmosphere external of said container and that within said container for selectively closing said pressure relief passage during reformation of said deformable means and for permitting the pressure within said container to return to that of the external atmosphere after reformation of said deformable member to its undeformed condition.

4. The filling device as set forth in claim 3 wherein said valve means includes a flap of deformable material mounted on said deformable means and displaceably covering said pressure relief aperture therein.

5. The filling device as set forth in claim 3 wherein said pressure relief aperture is in the form of an elongate radially disposed slit having upwardly directed side walls normally biased into engagement with each other, said side walls serving as said valve means during reformation of said deformable means.

6. A device for filling writing instruments of the type having an ink reservoir and a writing tip in fluid communication therewith comprising an open-ended ink supply container, deformable means hermetically secured to the open end of said ink supply container and displaceable thereinto for effecting a volume decrease therein, a writing instrument-receiving unit mounted on said deformable means shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, a displaceable pressure plate disposed on the upper surface of said deformable means for effecting a uniform manual displacement of said deformable means into said container, said deformable means and said pressure plate having an aligned pressure relief passage therein connecting the interior of said container with the atmosphere ex-

ternally of said container sized to permit substantial maintenance of atmospheric pressure within said container during deformation of said deformable means inwardly of said container, valve means mounted on said plate responsive to the difference in pressure between that of the atmosphere external of said container and that within said container for selectively closing said pressure relief passage during reformation of said deformable means and means for permitting the pressure within said container to return to that of the external atmosphere after reformation of said deformable member to its undeformed condition.

7. The filling device as set forth in claim 6 including actuating button members disposed in extending relationship on the upper surface of said pressure plate and a recessed closure member covering said deformable means and pressure plate apertured to permit displacement of said button members relative thereto.

8. The filling device as set forth in claim 6 wherein said valve means includes a flap of deformable material mounted on the upper surface of said pressure plate and displaceably covering said pressure relief aperture therein.

9. The filling device as set forth in claim 6 wherein said conduit member is provided with a portion of the surface thereof normally biased in substantially liquid-tight sealing relationship.

10. The filling device as set forth in claim 6 wherein said last mentioned means includes a relatively small venting channel in said pressure plate intersecting said pressure relief passage therein, said channel being operatively associated with said valve means in such manner that the effective cross-sectional area thereof is determined by the disposition of said valve means relative to said pressure relief passage.

11. A device for filling writing instruments of the type having an ink reservoir and a writing tip including a nib portion in fluid communication therewith comprising an open-ended ink supply container, a deformable diaphragm hermetically secured to the open end of said ink supply container and displaceable thereinto for effecting a volume decrease therein, a writing instrument-receiving unit mounted on said deformable means shaped to receive and engage the writing tip of a writing instrument inserted therein in substantially hermetic relationship, a conduit member dependent from said writing instrument-receiving unit shaped to receive the nib portion of a writing instrument inserted in said receiving unit and to connect the ink reservoir of said writing instrument in fluid communication with the interior of said container, a manually displaceable pressure plate disposed on the upper surface of said deformable means for effecting a uniform deformation and displacement of said deformable means into said container, said deformable means and said pressure plate having an aligned pressure relief passage therein connecting the interior of said container with the atmosphere externally of said container sized to permit substantial maintenance of atmospheric pressure within said container during deformation of said deformable means inwardly of said container, valve means mounted on said plate responsive to the difference in pressure between that of the atmosphere external of said container and that within said container for selectively closing said pressure relief passage during reformation of said deformable means and a venting channel associated with said pressure relief aperture and said valve means for permitting the pressure within said container to return to that of the external atmosphere after reformation of said deformable member to its undeformed condition.

12. A device for filling writing instruments of the type having an ink reservoir and a writing tip in fluid communication therewith comprising an open-ended ink supply container, deformable means hermetically secured to the open end of said ink supply container and displaceable thereinto for effecting a volume decrease therein, a writing instrument-receiving unit mounted on said de-

formable means shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, a displaceable pressure plate disposed on the upper surface of said deformable means for effecting a uniform manual displacement of said deformable means into said container, said deformable means having an elongate radially disposed pressure relief passage therein connecting the interior of said container with the atmosphere externally of said container sized to permit substantial maintenance of atmospheric pressure within said container during deformation of said deformable means inwardly of said container, said pressure relief passage including upwardly directed side walls sized to extend through said pressure plate and responsive to the difference in pressure between that of the atmosphere external of said container and that within said container for selectively closing said pressure relief passage during reformation of said deformable means and means associated with said side walls for permitting the pressure within said container to automatically return to that of the external atmosphere after reformation of said deformable member to its undeformed condition.

13. A device for filling writing instruments of the type having an ink reservoir and a writing tip in fluid communication therewith comprising an open-ended ink supply container, annular deformable means peripherally secured in hermetic relation to the open end of said ink supply container, a pressure plate hermetically secured to said deformable means and displaceable into said container for effecting a volume decrease therein, a writing instrument-receiving unit mounted on said pressure plate shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, said pressure plate having a pressure relief passage therein connecting the interior of said container with the atmosphere externally of said container sized to permit substantial maintenance of atmospheric pressure within said container during displacement of said pressure plate and deformable means inwardly of said container, valve means mounted on said writing instrument-receiving unit responsive to the difference in pressure between that of the atmosphere external of said container and that within said container for selectively closing said pressure relief passage during reformation of said deformable means and means for permitting the pressure within said container to return to that of the external atmosphere after reformation of said deformable member to its undeformed condition.

14. A device for filling writing instruments of the type having an ink reservoir and a writing tip in fluid communication therewith comprising a deformable ink supply container responsive to manual deformation thereof for effecting a volume decrease therewithin, a writing instrument-receiving unit mounted on said container shaped to engage the writing tip of a writing instrument inserted therein in substantially hermetic relationship, a conduit member dependent from said writing instrument-receiving unit for connecting the ink reservoir of a writing instrument inserted in said receiving unit in fluid communication with the interior of said container, said deformable container having a pressure relief passage therein connecting the interior of said container with the atmosphere externally of said container sized to permit substantial maintenance of atmospheric pressure within said container during deformation thereof, valve means responsive to the difference in pressure between that of the atmosphere external of said container and that within said

15

container for selectively closing said pressure relief passage during reformation of said container and means for permitting the pressure within said container to return to that of the external atmosphere after reformation thereof to its undeformed condition.

15. A device for filling writing instruments of the type having an ink reservoir and a writing tip in fluid communication therewith comprising an ink supply container having inwardly deformable side walls and an integral manually displaceable pressure plate for effecting a volume decrease therewithin, a writing instrument-receiving unit mounted on said pressure plate shaped to engage the writing tip of a writing instrument inserted therein in substantially hermetic relationship, a conduit member dependent from said writing instrument-receiving unit for connecting the ink reservoir of a writing instrument-in-

16

serted in said receiving unit in fluid communication with the interior of said container, said pressure plate having a pressure relief passage therein connecting the interior of said container with the atmosphere externally of said container sized to permit substantial maintenance of atmospheric pressure within said container during deformation of said deformable means inwardly of said container, valve means responsive to the difference in pressure between that of the atmosphere external of said container and that within said container for selectively closing said pressure relief passage during reformation of said container and means for permitting the pressure within said container to return to that of the external atmosphere after reformation thereof to its undeformed condition.
